his Attorneys.

Witness: N. C. McKey.

Patented Apr. 13, 1926.

UNITED STATES PATENT OFFICE.

MICHAEL W. MCARDLE, OF CHICAGO, ILLINOIS.

STROP FOR SAFETY-RAZOR BLADES AND THE LIKE.

Application filed January 28, 1925. Serial No. 5,192.

To all whom it may concern:

Be it known that I, MICHAEL W. MCARDLE, a citizen of the United States, residing in Chicago, in the county of Cook and the State of Illinois, have invented certain new and useful Improvements in Strops for Safety-Razor Blades and the like, of which the following is a specification, reference being had to the accompanying drawings, forming a part thereof.

The purpose of this invention is to provide an improved device of the nature of a strop for a safety razor blade and like implements, having straight edges to be sharpened. It consists in the elements and features of construction shown and described, as indicated in the claims.

In the drawings:

Figure 1 is a perspective view of a device embodying this invention, showing the mode of use in the hands of the user.

Figure 2 is an end elevation of the device shown in Figure 1.

Figure 3 is a section at the line, 3—3, on Figure 2, showing one form of the means of securing and tightening the strap and mounting the handle.

Figure 4 is a detail section at the line, 4—4, on Figure 1 for illustrating the co-operation of the fingers of the user with the blade and sharpener in sharpening.

Figure 5 is a detail fragmentary view showing the two ends of the strap withdrawn from their lapped position for showing the means by which they are engaged for tightening on the mount in the form shown in Fig. 3.

Figure 6 is a section at the line, 6—6, on Figure 3.

Figure 7 is a view similar to Figure 3 showing a modified and preferred form of the means for securing and tightening the strap.

Figure 8 is a section at the line, 8—8, on Figure 7.

A defect which may be observed in the more customary devices for sharpening razor blades and the like, is that the sharpening device,—strap or inflexible sharpener,—is either concave or flat at the surface along which the blade is moved or which is movable across the blade for sharpening, tending to cause the angle of bevel of the edge of the blade which is to be sharpened to be rendered more obtuse, rather than more

acute, by the process of stropping or honing. In the present invention this defect is avoided and the contrary tendency is obtained by making the strop surface over which the blade is manipulated for sharpening convex, and with approximately cylindrical form of curvature. In the structure shown in the drawings A is a metal mount for the sharpening strap. It is formed of a strip of quite stiff, and preferably somewhat resilient, metal flexed as to its middle part in substantially the form of a cylindrical segment, the ends being bent toward each other and lapped to form the base of the cylindrical segment. Desirably the two ends lapped at ⁶⁰ _a are permanently secured together as by spot-welding or the like, and at their lap are apertured as seen at ⁶⁵ _{a¹}, at the central point of the base of the segment form. The strap, B, is wrapped about the mount, A, ⁷⁰ the middle portion extending over the curved portion of the mount. For securing the ends together and tightening the strap about the mount in the form shown in Figure 3, the construction comprises metal plates, C, ⁷⁵ C, secured as by rivets, c, upon the lapping end portions of the strap, the strap and the metal plates being provided with elongated slots, ⁸⁰ _{b¹} and _{c¹}, respectively, the metal plates having rack teeth as seen at _{c²}, on one side ⁸⁵ or the slot, the plates on the two ends of the strap respectively having the rack teeth at the opposite sides of the slot, as may be understood from Figures 5 and 6. A pinion, D, dimensioned and toothed for entering ⁹⁰ the slots and engaging the rack teeth at the opposite sides of the slots in the metal plates respectively, is mounted on a handle, E, which extends down from the center of the base of the segment, having a flange, F, below the pinion, D, said flange being diametered for lapping the margins of the slot of the lower or outer-lapped end of the strap. This handle has the reduced end by which it extends through and engages the pinion ¹⁰⁰ extended beyond the pinion at the inner or upper side and threaded for receiving a nut, G, whose diameter is greater than the diameter of the aperture, _{a¹}, in the base of the mount, whereby the nut serves to retain the handle. From this description it may be understood that when the handle is entered and the pinion thereon engaged with the racks, C¹, C², the rotation of the handle ¹⁰⁵ serves to tighten the strap on the mount, ¹¹⁰

and that the nut G, being then tightened, will serve to retain the strap stretched to the desired degree of tightness.

In the form shown in Figures 7 and 8, instead of the means described and shown in Figures 3, 5 and 6, for securing and tightening the strap, the means for that purpose comprises a clamp fitting consisting of a nut or bushing, M, diametered for being entered 10 through the aperture, a^1 , in the base of the mount, A, having a radially projecting flange, m, at the inner end, having its outer end reduced and threaded at m^1 , and its axial aperture threaded as seen at m^2 . This fitting 15 is dimensioned as to its length from the inner face of the flange, m, to the shoulder produced by the reduction at the threaded end, m^2 , for extending through the lapped ends, a, a, of the base of the mount and nearly 20 through the lapped ends of the strap which are preferably re-enforced by metal plates, d^1 , as seen in Figure 7; so that a nut, N, screwed onto the reduced threaded end, n^2 , against an interposed washer, O, serves to 25 clamp the lapped ends of the strap securely onto the base. In this construction these lapped ends are not slotted and no provision is necessarily made at this point for increasing the lap for stretching the strap, the strap being dimensioned as to its length for fitting 30 fairly snugly around the mount to bring the apertures at its ends registered with each other and with the base in the mount. The means for tightening the strap in this form 35 consists of a strut which as shown comprises a stem, P, and a cross head, R, the cross head extending the entire width of the mount A, and bearing up against the under side thereof at the middle point, and having at the 40 middle point of its length a hollow boss, r, in which the end of the stem, P, is seated. This stem is reduced in diameter as to its upper portion and threaded for a short distance below said reduced portion for screwing 45 through the fitting, M, to project the cross head, R, up against the under side of the cylindrical seat afforded by the mount for the strap, and whereby, in view of the 50 resilient yieldingness of the mount it is expanded and thereby tends to stretch the strap mounted thereon. Desirably this threaded stem, P, is made as a continuation of the handle, E and is furnished with a lock nut, T.

It will be understood from the illustration in the drawings, and particularly in Figure 4, that in the use of this blade strop, the blade, W, being held between thumb and finger of the operator, will be positioned as 60 to its angle to the sharpening surface of the strap, by the thumb or finger-nail of the operator resting and being kept in contact with the strap as the blade is drawn over the curved surface; and that this prevents 65 the blade being inclined at any time to a

tangent of the curve at an angle tending to blunt the blade by reason of the bevel of the cutting edge being less than it should be for maximum efficiency.

I claim:—

1. A device for the purpose indicated consisting of a mount having an arcuate surface, the same being made of a metal strip formed as to its middle portion in the arc of a segment of a cylinder 75 and having the end portions extending in the plane of the chord of such segment, and united to form the base of the mount, said base being apertured near the middle point, a strap of material suitable for blade sharpening purposes stretched on said arcuate surface of the mount; means for securing the strap being a clamping device adapted to pass through said aperture radially flanged at one end and threaded at the 80 other end, and a clamping nut applied to the threaded end, the strap being apertured near its ends and lapped in engagement with said threaded fitting and clamped thereon between the nut and the outer side 85 of the base of the mount.

2. A device for the purpose indicated consisting of a mount having an arcuate surface, the same being made of a strip of resilient metal formed as to its 95 middle portion in the arc of the segment of the cylinder and having the end portions extending in the plane of the chord of such segment and united to form a base of the mount, said base being apertured near its 100 middle point; a strap of material suitable for blade sharpening purposes stretched on said arcuate surface of the mount; means for clamping the strap on the mount by the ends of the strap wrapped and lapping on the base, consisting of a fitting having 105 one end radially flanged, and the other end exteriorly threaded, adapted for insertion through the aperture of the base, and the apertures of the strap, and provided with a nut for screwing onto the threaded ends for clamping the lapped strap ends against the base, said fitting being axially apertured and interiorly threaded, and means for 110 tightening the strap consisting of a cross bar seated against the under side of the cylindrical portion of the mount and a stem engaged rotatably with said cross bar screwed through the clamp fitting and provided with means for rotating it to thrust 115 it against the cross bar.

3. A device for the purpose indicated consisting of a hollow member having an arcuate surface having an aperture substantially centrally positioned in the side opposite said arcuate surface, the same constituting a mount; a strap for sharpening purposes stretched on and adapted to enwrap the said arcuate surface of mount and lap its ends over said aperture, and 125 130

having apertures for substantial registration with the aperture of the base; means for clamping the strap ends onto the base at said registering apertures; a strut device extending between said clamping means and the under side of the curved portion of the mount comprising a cross bar at its bear-

ing under said curved portion, and means for extending the strut between said clamping means and said cross head. 10

In testimony whereof, I have hereunto set my hand at Chicago, Illinois, this 23rd day of January, 1925.

MICHAEL W. McARDLE.
